JAMES CASSEL Inventor

By
Richard Blewer Attorney

UNITED STATES PATENT OFFICE.

JAMES CASSEL, OF PERU, INDIANA.

BURIAL CASKET.

Application filed November 10, 1923. Serial No. 674,042.

To all whom it may concern:

Be it known that I, JAMES CASSEL, a citizen of the United States, residing at Peru, in the county of Miami and State of Indiana, have invented certain new and useful Improvements in a Burial Casket, of which the following is a specification.

This invention appertains to burial caskets formed of vitreous material and the primary object of the present invention is to provide a novel burial casket formed of glass or similar material, which will successfully resist deterioration from the elements and maintain the corpse therein in good condition.

Another prime object of the invention is to provide a glass burial casket embodying a body portion and a cover, and novel means for associating the cover with the bottom portion, so as to prevent the entrance of air into the casket.

A further object of the invention is to provide a glass burial casket having a pivoted drop side formed in the body thereof, and novel means for insuring an airtight connection between the drop side and the body, when the drop side of the casket is in its raised operative position.

A further object of the invention is to provide novel means for associating the carrying rods with the sides of the casket.

A still further object of the invention is to provide an improved burial casket of the above character, which will be durable in use, one that will be simple and easy to manufacture and one which can be placed upon the market at a reasonable cost.

With these and other objects in view, the invention consists in the novel construction, arrangement and formation of parts, as will be hereinafter more specifically described, claimed and illustrated in the accompanying drawings, in which drawings;

Figure 1 is a side elevation of the improved burial casket.

Figure 2 is a plan view of the casket.

Figure 3 is a transverse section through the casket taken on the line 3-3 of Figure 1.

Figure 4 is a vertical longitudinal section through the improved casket taken on the line 4-4 of Figure 3.

Figure 5 is a fragmentary horizontal section through the casket taken on the line 5-5 of Figure 4.

Figure 6 is an enlarged detail horizontal section taken through one side of the casket illustrating the novel means for associating the carrying rods or handles therewith.

Figure 7 is a detail vertical section through one end of the casket illustrating the means employed for connecting the cover and the body of the casket together, and

Figure 8 is a detail vertical longitudinal section through the lower wall or bottom of the casket illustrating the means of associating the supporting feet therewith.

Referring to the drawings in detail, wherein similar reference characters designate corresponding parts throughout the several views, the letter A generally indicates the improved casket, which is adapted to be formed of glass, of a relatively high grade and of a transparent nature, so that the corpse contained therein can be readily viewed.

As shown the casket A comprises a body portion 10 and a cover portion 11.

The body portion 10 includes a flat bottom wall 12, upstanding side walls 13 and 14 and end walls 15. The end wall 13 is provided with a drop side 16 and this wall is cut out to receive the same. The drop side 16 is preferably connected with the wall 13 by means of suitable hinges 17 clearly shown in Figures 1 and 3 of the drawings. The top edge of the drop side 16 is flushed with the top edge of the side and end walls 13, 14, and 15. It is preferred to have the upper edges of the side walls 13, 14 and the end walls 15 and the drop side 16 rabbeted as at 18 for a purpose, which will be hereinafter more fully described.

The cover 11 for the body 10 comprises a top wall 19, depending side walls 20 and 21 and end walls 22. The lower edges of the side walls 20, 21 and the end walls 22 of the cover 11 are also rabbeted as at 23 to fit the rabbeted portions 18 of the body 10 of the casket and it can be seen that this forms a tight joint, and in order to prevent the entrance of air into the casket, suitable compressible gaskets 24 can be provided, which are disposed between the meeting edges of the cover and body portions of the casket.

In order to maintain the cover 11 tightly on the body 10 I provide novel means for connecting the same together. As

shown, the end walls 22 of the cover 11 support eyes 26, the shank 27 of which extend through the said end walls 22 and in order to prevent the seeping of air into the casket 5 around the bolts, suitable gaskets 28 can be placed around the shank 27 in intimate contact with the said cover. The end walls 15 of the body 10 of the casket directly below the eyes 26 carry hooks 29, the shanks 30 of 10 which extend through the end walls 15 and are also placed gaskets 31 on the shanks 30 so as to prevent the creeping of air into the casket. The hooks 26 carry chains 32, any one of the links of which are adapted 15 to hook over the hooks 29. It is evident that this will maintain the cover securely on the body.

In order to prevent the seeping of air into the casket around the edges of the drop 20 side 16 and in order to make a firm joint, I provide a frame 35, which can be secured by bolts, rivets or the like to the wall 13 around the cutout portion formed in the said wall for receiving the drop side and it can 25 be seen that when the drop side is in its raised position, that the same will abut the frame 35. A compressible gasket 36 is carried by the base of the frame 35 adjacent to the drop side 16 and thus it is evident that 30 this gasket will be compressed when the drop side is moved to its raised position.

In order to facilitate the placing and removing of the cover 11 from off and on the body portion 10, I provide handles 40 for 35 each side wall 20 of the cover. These handles are preferably of an ornamental nature and can be nickel plated if so desired. These handles can be bolted or riveted in place, as shown in Figure 4 of the drawings.

40 To facilitate the easy carrying of the casket, I provide longitudinally extending rails or carrying handles 45, which are attached to the body portion 10 of the casket in a novel manner. As shown the side walls 45 13 and 14 of the body portion adjacent to each end thereof carry outstanding flat eyes 46 which are connected in any preferred way to the terminals of transverse rods 47 which extend entirely through the walls 13 and 14 and these rods can have gaskets 48 around the same for engaging the said walls of the casket to form a tight joint therewith. These rods 47 can be utilized for supporting the weight of the corpse and also for supporting the weight of the casket, when the same is being carried by the handles 50. A rod 49 is extended through the eyes 46 and if so desired an ornamental sleeve suitably nickel-plated or the like 50' is placed on the rod 49 between the eyes. The ends of the rods 49 are threaded for receiving ornamental ball end caps 51, which also can be nickel plated.

The lower wall 12 supports pads or feet

60, and as shown these pads or feet 60 are 85 preferably formed of rubber molded onto the ends of bolts 61, which are extended through the bottom wall 12 and held in place in any desired way.

The top wall 19 of the cover 11 carries a 70 suitable name plate 65 and a name and a suitable epitaph can be engraved, burnt in, molded or otherwise formed therein.

From the foregoing description, it can be seen that I have provided an exceptionally 75 simple and durable casket, which is so constructed as to preclude the entrance of air therein and effectively resist deterioration from the elements.

Changes in details may be made without 80 departing from the spirit or the scope of this invention.

What I claim as new is:

1. A burial casket formed of vitreous material comprising an integral molded body portion, an integral molded cover portion, a drop side for the body portion, the upper edge of the drop side being flushed with the upper edges of the walls of the body, the upper edges of the walls of the body and the drop side being rabbeted, the lower edge of the cover being rabbeted to engage the rabbeted edges of the side walls and drop side, and means for connecting the cover with the body.

2. A glass burial casket comprising an integral molded body, having a drop side pivotally connected thereto, a metal frame carried by the inner surface of the body around the drop side, a gasket carried by the frame adapted to be engaged by the drop side when the same is in its operative position, and an integral cover arranged to engage the upper edge of the body portion and drop side.

3. In a glass burial casket, an integral body portion, an integral cover arranged to snugly engage the upper edge of the body portion, eyes carried by the side walls of the body portion including shanks extending through the said side walls, gaskets extending around the shanks engaging the side walls, longitudinally extending ornamental rods carried by the eyes and caps threaded upon the rods engaging said eyes to hold the rods against longitudinal movement in said eyes.

4. In a glass burial casket, a body portion, a cover arranged to snugly engage the upper edge of the body portion, eyes carried by the end walls of the cover portions, hooks carried by the end walls of the body portion arranged directly below said eyes, and chains carried by the eyes arranged to engage said hooks.

5. A burial casket comprising a body including side and end walls, a cover for the body, means for forming a tight closure between the body and the cover, means for

connecting the cover with the body, transverse rods disposed in the body adjacent to the lower end thereof for supporting a corpse, the terminals of said rods extending through the side walls of the body, and carrying members connected with the terminals of the said rods.

In testimony whereof I affix my signature in presence of two witnesses.

JAMES CASSEL.
